UNITED STATES PATENT OFFICE

2,277,923

COMBINED WASHING MACHINE AND DRIER

Charles E. Morgenstern, St. Joseph, Mich., assignor to Nineteen Hundred Corporation, Binghamton, N. Y., a corporation of New York

Original application June 22, 1936, Serial No. 86,522. Divided and this application December 27, 1937, Serial No. 181,844. In Canada June 19, 1937

4 Claims. (Cl. 68—26)

This invention relates to domestic laundry machines and particularly to such machines including in combination a washing machine and a centrifugal drier.

It has been a primary object of the invention to improve and simplify machines of the character specified and increase their efficiency in the performance of the washing and drying operations.

A special feature of the invention is the provision of improved means for supporting and centralizing the centrifugal drying basket so that it may be revolved at a high speed without producing undue vibrations of the machine as a whole. In this connection it has been found that centralizing forces applied to the basket supporting shaft intermediate its ends are much more effective when the forces are applied in an irregular or non-uniform manner. Thus, if forces are applied to the shaft at spaced intervals around a plane, they will act more quickly and effectively to stabilize the shaft if the spacing is not regular or equal between the successive points of application.

Another feature of the invention is the provision of simple but effective control devices for governing the operation of the drier and insuring application of the cover thereto whenever the drier is in operation. A simple arrangement is also provided for controlling the drainage devices associated with the washing and drying units in conjunction with the control of the operation of these units.

A further feature is the provision of a drain-board in association with the drier capable of readily assuming any one of a plurality of different positions, the construction for this purpose being simple and inexpensive.

In connection with the washing unit, an improved relationship has been provided between the agitator and tub. The agitator is of a type capable of setting up vigorous movements of the water in directions having a substantial component upwardly along the wall of the tub and therefore having a tendency to continue upwardly beyond the top of the tub, as normally constructed. Such a movement is produced by a single vane agitator of the type disclosed in Davis Patent No. 1,748,442, granted February 25, 1930. It has been found in the use of such an agitator at the speed and through the arc of travel desired for efficient washing of the clothes that the upward movement of the water is such as to cause the cover to be lifted and some of the water to be splashed from the machine.

According to a feature of the present invention, however, this difficulty is overcome by so forming the top of the tub as to cause the upwardly moving currents of water to be turned inwardly toward the center of the tub just beneath the cover.

Other features and advantages of the invention will appear from a detailed description of an illustrative form of the same which will now be given in conjunction with the accompanying drawings in which:

Fig. 1 is a vertical, longitudinal section through the upper portion of the machine, certain of the parts being shown in elevation;

Fig. 2 is a plan view of the machine, most of the cover for the dryer unit being broken away to disclose the interior of the dryer and the drainboard being shown in full lines in one position and in dot and dash lines in two other positions;

Fig. 3 is an enlarged detail in vertical section along the line 3—3 of Fig. 2;

Fig. 4 is a greatly enlarged horizontal section along the line 4—4 of Fig. 1;

Fig. 5 is a slightly enlarged horizontal section along the line 5—5 of Fig. 1;

Fig. 6 is an enlarged vertical section through a portion of the dryer unit;

Fig. 7 is an enlarged vertical section through the upper portion of the machine along the line 7—7 of Fig. 2;

Fig. 7a is a vertical section along the lines 7a—7a of Fig. 4, the parts being shown in proper relation to the devices of Fig. 7;

Fig. 8 is a detail view in section along the line 8—8 of Fig. 7;

Fig. 9 is a slightly enlarged horizontal section taken along the line 9—9 of Fig. 6 in the direction indicated by the arrows;

Fig. 10 is a similar, horizontal section taken along the line 10—10 of Fig. 6 in the direction indicated by the arrows;

Fig. 11 is an enlarged vertical section along the line 11—11 of Fig. 4;

Fig. 12 is a detail view in elevation along the line 12—12 of Fig. 6 with some of the parts broken away to better illustrate others;

Fig. 13 is a plan view of the devices shown in Fig. 12;

Fig. 14 is an elevational view, partly in section, taken along the line 14—14 of Figure 5 and showing the linkage for controlling the washing mechanism; and

Fig. 15 is a vertical section along the line

15—15 of Figure 6 showing a detail of the spinner drive.

Referring now to the drawings, the machine illustrated comprises a suitable support 10 having a substantially flat supporting surface at its top and a downwardly extending skirt or apron enclosing and concealing the operating devices of the machine. The support 10 is preferably carried by a series of legs 11, a fragmentary portion of only one of which is indicated in Fig. 1.

Four such legs may be employed to provide a sturdy support. On the upper surface of the support 10 there is mounted a washing compartment or tub 12, preferably cylindrical in form, and a similar cylindrical compartment or chamber 13 for the dryer. As shown, the dryer compartment may be considerably smaller in diameter than the tub, although its height is preferably the same. To eliminate vibration and noise as much is possible, the tub 12 is preferably supported adjacent its periphery by a rubber ring 14, or the like, while the dryer chamber may be similarly supported by means of a rubber ring 15, or the like.

To the under side of the horizontal portion of the support 10 there may be suitably attached a bracket 16 having downwardly extending arms arranged to carry a motor 17. The armature shaft 18 of the motor is connected by a universal coupling 19 with a shaft 20 journaled in a gear casing 21. This gear casing is suitably attached to the support 10 and has an upwardly extending neck 22 passing through an opening in the support 10 and through an opening in the bottom of the tub 12. A cooperating sleeve member 23 may serve to clamp the support and tub bottom together. This construction may suitably be of the form comprising a suitable stuffing box construction and other means may be employed within the sleeve 23 and the top of the gear casing to prevent leakage of water from the tub. A shaft 24 suitably journaled in the gear casing and sleeve 23 may carry a torque block 25 at its upper end adapted to receive and drive an agitator 26, which may be held in place on the shaft by a screw 27. The agitator 26 may be of any suitable construction but one that will produce violent agitation and movement of the water, such as a single vane construction of the type disclosed in the previously mentioned Davis patent, is preferable.

Any appropriate means may be provided for imparting an oscillatory or other rotary movement of suitable magnitude and speed to the shaft 24. For this purpose the shaft 20 may carry a worm adapted to mesh with a worm-wheel 28 carried by a stub shaft 29 suitably journaled in the gear casing. A pin eccentrically mounted on the worm-wheel may be connected by a link 31 with a pin 32 carried by a segment 33 mounted on a fixed pivot 34 within the gear casing. Segment 33 meshes with a broad-toothed pinion 35 forming part of a clutch unit having at its upper end a toothed member 36 adapted to cooperate with an internally toothed member secured to the shaft 24. As will be understood, the clutch member 35 is free to turn upon the shaft 24 but when lifted to engage the toothed portion 36 with the internally toothed member of the clutch, the shaft 24 will be oscillated in accordance with the movements of the segment. Preferably the shaft 24 will be caused to turn in this way through an arc of between 175 and 225° at a speed of between 50 and 75

complete to and fro movements per minute. Any appropriate means may be provided for lifting the clutch member 36, including, for example, a lever 361 (Fig. 14) connected with a link 37 operable by a two-armed lever 371 which in turn is operated by a rod 38. This rod is slideable longitudinally in suitable supports (not shown) by means of a knob 39 (Fig. 2) carried at its upper end. Upon depression of the knob the lever 371 is shifted to the broken-line position of Figure 14, an over-center spring 372 assisting in the final part of the movement, and the clutch is thereby engaged. If the clutch teeth are not properly aligned when first brought together, a spring (not shown) in the connection 37 will yield temporarily until the teeth are aligned. The knob 39 may be locked in depressed position in any suitable way, as by turning the same, to carry a pin on the shank thereof beneath some part of the casing. When it is desired to release the clutch the knob may be simply turned to align said pin with a slot so that a spring, capable of lifting the rod against the action of spring 372, will restore the parts to the full-line position of Figure 14. The pin and spring, just mentioned, are not shown but may be similar to those associated with the spinner control knob 133, to be later described.

The tub 12 is preferably provided at its center with a depressed well 40 into which the bottom disc portion of the agitator 26 may be set with a relatively close fit. From the top of the well the portion 41 of the bottom of the tub preferably slopes upwardly at a slight angle toward the side walls of the tub. A gentle curvature is preferably employed, as indicated at 42, between the bottom and side walls of the tub. This arrangement enables the free, easy movement of the water and clothes outwardly and upwardly as the agitator is oscillated. At the top of the tub the side walls are curved inwardly along a sweeping 90° arc of relatively large radius, as indicated at 43. This curved portion at the top is preferably made integral with the side wall. In the oscillation of an agitator of the single vane type, currents of water are thrown violently outward toward the wall of the tub and these currents travel upwardly as well as around the wall with considerable momentum and velocity. It has been found that if the tub is provided with an opening at the top substantially equal to the diameter of the side walls, or if the top is simply closed partially by a flange extending inwardly at a sharp angle from the side walls, there is a tendency for all or part of the water to move straight up through the opening at the top, lifting the cover if one is applied over the opening. However, when the top of the tub is curved inwardly, in the manner shown in Fig. 1, the upward movement of the water is gradually converted into an inward movement and there is no tendency for the water to lift the cover or splash out of the tub. Even though the upwardly moving wall of water may be of substantial thickness, the curvature 43 at the top of the tub is sufficient to direct the water inwardly across the top of the tub without rising above the top of the tub, particularly when clothes are mixed with the water. Preferably the inner edge of the curved portion 43 is formed to provide a slight neck 44 at the top of the tub, which may conveniently receive a rubber gasket 45 to support a cover member 46. This construction places the bottom of the cover slightly above a line tangent to the curved surface 43 adjacent

its inner edge. Accordingly, there will be no tendency to lift the cover and cause water to be splashed out of the machine. It should be observed in connection with this feature of the construction that the problem referred to above does not arise when a multiple vane agitator is used. The character of the water current set up by the common multiple vane type of agitator is such that the water does not tend to rise appreciably above its normal level and therefore does not tend to lift the cover and splash out of the machine.

Turning now to the drying unit, there is provided within the chamber or compartment 13 a perforated basket 47. This basket is preferably substantially cylindrical but with its upper end sloping inwardly to partially close the same. Substantially the entire vertical wall is provided with a series of perforations to permit the discharge of water as the basket is rotated at a high speed, in the manner to be explained. The bottom of the basket is preferably formed by a casting 48, having an upwardly extending portion 49 at its center provided with a sleeve 50 adapted to snugly receive the upper end of a shaft 51. A pin 52, carried by the projection 49 adjacent its upper end, is adapted to fit into a notch or groove 53 in the upper end of the shaft 51. In this way the rotation of the shaft is imparted to the basket. The upper end of projection 49 is preferably closed by a screw cap 54, or the like.

Shaft 51 is journaled in a bearing sleeve 55, formed of bronze or other good bearing material, mounted in an extension 56 of a casing 57. The extension 56, as shown, is preferably provided on a separable cover member bolted to the main portion of the casing 57. At its lower end this casing is formed with a downward extension 58, preferably square in cross section. A rubber projection 59, similarly square in cross section, surrounds the projection and fits within a pocket provided by a member 60. The latter is carried by a strap 61 secured by bolts 62 to a bracket 63 suitably secured to the main support 10. The member 60 is preferably secured to the strap 61 by means of bolts 64 passing through elongated slots 65 in the strap. This arrangement is such that the angular relation between the member 60 and the strap 61 may be varied slightly to properly align certain shafts, the necessity for which will be made clear hereinafter. Beneath the strap 61 there is provided a disc 66 of rubber or other resilient material, preferably having a reduced portion extending through an opening in the strap and engaging the lower end of the projection 58. A metal plate or washer 67 is provided beneath the disc 66 and a bolt 68 is employed to retain these parts in assembled relation. It will be apparent that through the construction described the casing 57 will be supported by the strap 61 in a position to maintain the axis of the shaft 51 substantially vertical. However, due to the rubber or other resilient bushing 59 and disc 66, the casing may be tilted slightly in any direction.

In order to assist in maintaining the substantially vertical alignment of the shaft 51 without, however, rigidly confining the shaft, resilient means are provided for applying forces of the character hereinbefore specified at a point some distance up from the lower end of the casing 57. For this purpose a collar 69 is provided around the extension 56 of the casing, this collar being rigidly secured to the extension and having a pair of laterally projecting wings 70. Each of these

wings is provided with a pair of apertures to receive the ends of springs 71. The opposite ends of these springs are attached to pins 72, each carried by a bracket 73 secured to the under side 5 of the main support 10. The pins 72 are threaded for at least a portion of their length to receive nuts 74 which may be adjusted to any position desired and locked therein in any suitable way. By so adjusting these nuts the tension on the various springs 71 may be varied to suit the 10 particular requirements. It will be observed that the springs 71 are not uniformly distributed around the axis of the casing but are arranged to apply a greater restraining force to the movement of the casing in certain directions than in others. It will be appreciated that when the basket is being rotated at high speed, the uneven distribution of the clothes therein will tend to produce a greater centrifugal force at the point 15 where the load is in excess. As a result of this uneven distribution of the load, the upper end of the shaft 51 will have a tendency to move in a gyratory path as it rotates. If an attempt were made to rigidly confine the shaft with relation to the main support 10, the forces tending to move the shaft in a gyratory path would be imparted to the frame and would thus set up very objectionable vibrations therein. However, these 20 vibrations are eliminated or reduced to an unobjectionable minimum by the application of resilient forces to the shaft, in the manner disclosed, to retain it in or restore it to its normal position. As the machine is set into operation, the upper end of the shaft 51 tends to move in a gyratory or orbital path but the magnitude of this path is very quickly reduced by the action of the springs 71 as the basket attains the desired speed. Suffice it to say, without attempting to 25 explain the reason for it, the non-uniform arrangement of the springs 71 assists very materially in promptly reducing the extent of the gyratory motion and preventing it from attaining an objectionable magnitude.

Means are preferably provided for effecting a seal at the bottom of the container 13 to prevent the discharge of water along the shaft 51. For this purpose a member 75 is provided around the shaft, this member having a laterally extending flange at its base which may be secured to the bottom of the container 13. A gasket 76 is preferably provided between the member 75 and the bottom of the container. Any suitable means, such as screws 77, may be employed for securing the member 75 to the container bottom. Member 75 extends upwardly into a recess formed in the bottom member 48 of the basket. The top of the member 75 is thus maintained at a level normally above the level at which water will accumulate within the container. However, should water rise above this level, it is prevented from passing downwardly between the member 75 and shaft 51 by means of a flexible diaphragm 78 formed of rubber or other suitable material. This diaphragm preferably has an annular portion, U-shaped in cross-section, fitting over the upper end of the member 75 and has another annular portion surrounding a sleeve 79 secured to the shaft 51. A sufficiently tight fit is provided between the diaphragm and the sleeve 79 to substantially prevent the passage of any water along the shaft. However, should any small amount of water find its way along the shaft it will be deflected by an outwardly flaring shield 80 carried by the shaft beneath the sleeve 79. This shield or deflector will divert such water

outwardly over the extension 56 and will prevent its passage into the interior of the casing 57 which carries a lubricant.

The lower end of the shaft 51 is reduced in diameter and is surrounded by a sleeve 81, Figure 15, which fits snugly in a recess 82 in the extension 58 of the casing 51. Moreover, the lower end of shaft 51 is formed with a recess 83 carrying a series of balls 84, the lowermost of which extends slightly beyond the lower end of the shaft and bears against a disc 85. Beneath this disc is a large ball 86 supported by a disc 87 carried at the lower end of the recess 82. In this way the vertical thrust of the shaft 51, together with the basket 47, is transmitted to the 15 casing 57.

Mounted on the sleeve 81 and secured thereto is a spiral gear 88 adapted to mesh with a similar spiral gear 89 (Figs. 10 and 15) secured to a shaft 90 carried by bearings 91 and 92 integral with the casing 57. The end thrusts of the shaft 90 are taken by a disc 93, ball 94 and a second disc 95 mounted in the end of the recess forming the bearing 92. Shaft 90 is connected by a universal coupling 96 with one end of the shaft 18 of motor 17. As best shown in Figs. 1 and 5, the motor shaft 18 is connected at one end to drive the agitator of the washing machine and is connected at its other end to drive the basket 30 of the dryer. Adjacent its upper end the sleeve 81 is provided with a laterally extending flange 97 to which is secured a disc 98. Normally the weight of the sleeve 81 and its connected parts will be sufficient to cause the latter to rest upon the bearing disc 85. However, the arrangement 35 of the teeth on the spiral gears 88 and 89 is such that in driving the sleeve 81 against any substantial resistance, the sleeve will be raised until the disc 98 strikes a shoulder 99 (Fig. 15) formed slightly above it by enlargement of the shaft 51. 40 This will serve to lift the lower end of sleeve 81 from the disc 85 and eliminate friction at this point. Continued upward movement of the sleeve due to the vertical thrust produced by the spiral gears will tend to lift the shaft 51 and the basket. However, the arrangement is such that in the normal operation of the machine the various forces acting upon the shaft 51 are substantially balanced so that friction is reduced to a minimum but the basket is actually not lifted 45 to any appreciable extent.

The portion of the shaft 51 directly below the bearing is provided with a series of splines 100 cooperating with internal splines on a sleeve member 101. This sleeve member is, therefore, adapted to be rotated with the shaft and may be shifted longitudinally of the shaft. The lower end of the sleeve member is provided with an annular flange 102 carrying an annular friction member 103 adapted to cooperate with the disc 98. A spring 104 compressed between a collar 105 secured to the shaft 51 and the upper end of sleeve member 101 urges the latter downwardly to provide frictional driving engagement between the members 98 and 103. So long as this frictional engagement is maintained the basket 47 will be rotated, i. e., whenever the motor 17 is in operation. To disconnect the basket from the motor the sleeve member 101 must be lifted to disengage the friction surfaces. For this purpose member 101 has secured to its upper end an annular plate 106 arranged to be engaged by a friction element 107 carried by an annular member 108. Member 108 is provided with a pair 50 of downwardly extending ears 109 connected with

opposite ends of a yoke 110 by means of pins 111. Yoke 110 is secured to a shaft 112 carried by bearings provided in an extension of the casing 57. A screw 113 cooperating with a notch or cut-out portion of the yoke 110 serves to retain the latter and the shaft 112 against axial movement without, however, preventing a limited rocking movement of these parts. At one end of the shaft 112 there is secured an arm 114 carrying at its free end a roller 115. At the plane of the roller 115 there is provided an arm 116 carried by a stud 117 mounted on the frame of the machine. The free end of arm 116 is formed with a camming surface 118 arranged to engage the roller 115 as the arm is rocked downwardly and thereby rocks the shaft 112 counter-clockwise (Fig. 1a) to lift the member 107 into engagement with member 106 and upon the continued movement of member 107 the sleeve 101 will be raised against the action of spring 104. This serves not only to break the driving connection between the members 103 and 98 but also applies a brake between members 106 and 107 since the latter is held fixedly against rotational movement.

For the purpose of rocking the arm 116 in the manner explained, it has integrally or otherwise connected therewith an arm 119 to which is attached a spring 120, the opposite end of which is connected with the frame of the machine. It will be apparent that spring 120 tends to rock the parts in the direction in which surface 118 will engage roller 115 to disengage the friction clutch and apply the brake in the manner explained. When it is desired to operate the dryer, it is necessary to depress the arm 119 against the action of spring 120. For this purpose the arm is bifurcated at its outer end, as indicated at 121, and is fitted between nuts 122 carried at the lower end of a vertically extending rod 123. The upper end of this rod slides in an apertured guide member 124 carried by a member 125 carried at the top of the machine and forming a closure for the space between the tub 12 and drying chamber 13. A collar 126 secured to rod 123 abuts against the lower side of the guide member 124 to limit the extent of the rocking movement of the arm 119 by the spring 120. The top member 125 has an annular rim 127 adapted to fit over a gasket 128 carried at the top of the chamber 13. A detachable cover 129 is arranged to close the top of the chamber 13 and for this purpose is provided with an annular sealing member 130, formed of rubber or the like, extending around its periphery and adapted 55 to rest upon the upper surface of the rim 127. At one side of the cover there is secured, as by means of rivets or the like, a bracket 131 terminating at its outer end in a vertical guide sleeve 132. In this sleeve there is mounted, for both rotary and axial movement, the shank of a 60 control knob 133. To this knob is attached a downwardly extending rod 134 in axial alignment with the rod 123. A pin 135 extending through the rod 134 may be aligned, by proper rotation of the knob 133, with an elongated passage 136 formed through a boss on the top member 125. When the pin and passage are aligned a spring 137 serves to urge the knob into the dotted-line position of Fig. 7, in which the pin engages the 65 surface 138 within the sleeve portion of the bracket 131. This lower portion of the sleeve may be conveniently so formed as to hold the pin, and hence the knob, in a definite position so that when the cover is in place the pin will 70 be properly aligned with the passage 136. The

knob, when depressed into the full-line position shown, may be rotated to place the pin 135 at right angles to the passage 136 and thereby retain the knob in its depressed position. This also serves to lock the cover 129 with relation to top member 125. When the knob is depressed and locked in this position, furthermore, the lower end of rod 134 will engage and depress the rod 123 against the action of spring 120 and rock the arms 116 and 119 into the positions indicated in Fig. 7a. This will permit the spring 104 to slide the member 102 out of braking position and into frictional engagement with the driving member 98.

A suitable drainage system is provided for discharging the water from the tub 12 at the end of a washing operation and also for discharging the water from the chamber 13 during the operation of the dryer. For this purpose a valve chamber 139 is provided to receive the water from both the tub and the drying chamber. A tube 140 extending upwardly at a slight angle to the horizontal from one side of the valve chamber is provided with a fitting 141 at its end attached to the bottom of the tub to receive the water therefrom when desired. A substantially vertical branch of the valve chamber is provided with a flange 142 adjacent its upper end, arranged to cooperate with the bottom of the drying chamber 13. A fitting 143 within the chamber 13 serves to clamp the valve chamber to the drying chamber and serves also as a strainer for this inlet to the valve chamber. As shown, the fitting 143 preferably is located in a slight depression 144 in the chamber 13. A shaft 145 extending transversely through the chamber 139 has secured to it a T-shaped valve support member 146 carrying a valve 147 at the end of one of the arms, arranged to cooperate with a valve seat 148 at the inner end of the line 140. A similar valve member 149, carried by the end of the other arm of the support 146, is arranged to cooperate with a seat 150 in the passage from the drying chamber. A pair of springs 151 (Fig. 4), surrounding the shaft 145 and abutting opposite sides of the valve chamber, serve to retain the valve structure in a properly centralized position.

At the outer end of the shaft 145 there is mounted a control member 152 which may be grasped by the operator and rotated to carry the valve 147 against seat 148 or valve 149 against seat 150. At the inner end of the shaft 145 there is mounted an arm 153, having connected to its outer end a spring 154 whose other end is secured to a pin 155 carried by the valve chamber. The arrangement of the spring 154 is such that it serves to hold the pair of valves in either of their extreme positions. As the valves are shifted past dead center, the spring 154 will assist in swinging them to close one passage and fully open the other. Intermediate the ends of the shaft 145 there is secured an arm 156 having a foot 157 (Fig. 7a) adapted to swing beneath the rod 123. When the parts are in the positions shown in Figs. 7 and 7a the valve leading from the drying chamber is open. It is not possible to reverse the condition of the valves due to the abutment of the foot 157 with the lower end of the rod 123 as soon as manual rotation of the shaft 145 is attempted. This insures proper drainage of the water from the drying chamber so long as the spinner basket is in operation and prevents the discharge of water from the tub at this time. Furthermore, should the valves be in the opposite position at the time the spinner is

set into operation, the rod 123, on being depressed for this purpose, will engage the foot 157 and swing the valves into the position indicated in Fig. 7a. It will be understood that the over-center spring 154 will assist in this operation.

A suitable pump is provided for withdrawing the water from the valve casing 139 and discharging it into a stationary laundry tub or any other suitable receptacle. This pump may comprise a pump chamber 158 (Figs. 1, 4, 5 and 6) carried by a series of rods 159 extending from the housing of the motor 17, in a direction parallel with the axis of the motor. A rotor carried by the shaft 18 of the motor operates within the chamber 158 to pump the water as desired. A connection 160 is provided between the intake side of the pump and the discharge side of the valve casing 139, while a hose or tube 161 is connected with the discharge side of the pump to convey the water to any desired point. A flexible hose may be provided for this purpose to enable convenient discharge of the water into any suitable receptacle.

Referring to Figure 2, there is shown a drain-board 162 which is adapted to be moved into any one of a plurality of different positions. For this purpose there is attached, by welding or the like, to the underside of the drainboard, a pair of lugs 163, each having a downwardly projecting foot portion adapted to enter one of a series of slots or apertures formed in projections 164 extending from the edge of the member 125. These slots are appropriately spaced and located to permit the drainboard to assume any one of a number of different positions, three such positions being indicated.

It is believed that the operation of the machine will be clear from the foregoing detailed description of its various parts. A brief résumé may be given, however, for convenience. The clothes to be laundered are first placed in the tub 12 with a sufficient quantity of water to provide an efficient washing action. The motor 17 is then set into operation by throwing a suitable switch and the knob 39 is depressed, and locked by turning the same, to engage the clutch member 36 with its cooperating member to set the agitator 26 into operation. After a desired washing period the knob 39 is turned to release the clutch and the clothes are removed from the tub 12 and placed in the basket 47 of the dryer. The lid 129 of the dryer is then set in place and the knob 133 depressed and rotated to place the pin 135 crosswise of the passage 136. Depression of the knob in this way depresses the rod 123 which in turn rocks the arms 119 and 116 against the action of spring 120 and permits the spring 104 to slide the member 101 downwardly, thereby disengaging the brake surfaces and engaging the friction clutch surfaces. This will set the spinner basket 47 into rotation. As the speed of rotation increases, the supporting shaft 51 will receive a gyroscopic movement which will increase in magnitude at the beginning but, when a certain speed is attained, will be reduced in magnitude by the action of the non-uniformly distributed springs 71. If the valves 147 and 149 were not in the correct position to permit discharge of the water from the chamber 13 when the knob 133 was depressed, the depression of this knob and the rod 123 would swing the valves into the correct position by the engagement of the lower end of rod 123 with the foot 157. Upon completion of the drying operation the knob 133 is simply rotated

to align the pin 135 with the passage 136 and the cover 129 is thereby released. Spring 120 then takes effect to rock the arm 116 downwardly engaging the roller 115 to lift the brake member 101 into engagement with the member 106. This also lifts the member 101 to disengage the friction clutch faces 99 and 103.

While an illustrative embodiment of the invention has been described in considerable detail, it will be understood that numerous changes may be made in the construction and operation of the various parts without departing from the general principles and scope of the invention. The terms and expressions employed herein are to be regarded as terms of description and not of limitation.

This application is a division of my copending application Serial No. 86,522, filed June 22, 1936, and which copending application describes and claims, among other things, the valve and drier operating device, the vibration elimination feature, the drier clutch, the clutch control, the drier drive, and the drain board. The novel features and characteristics of the agitating device were originally claimed in my copending application Serial No. 86,522 but were withdrawn from that particular application following a requirement for division.

What I claim is:

1. In apparatus comprising a pair of water-retaining chambers, a motor, a pump driven by said motor, means connecting said pump with each of said chambers, valve means for closing the connection between said pump and said chambers alternately, washing means in one of said chambers and drying means in the other of said chambers, the combination of separate control means for connecting said washing means and said drying means to said motor to be driven thereby, and an interlocking connection between the valve means and drying control means for operating said valve means to open the connection between said pump and the chamber having said drying means and simultaneously closing the connection between said pump and said chamber having said washing means whenever said drying means is connected to said motor to be driven thereby.

2. In apparatus comprising a pair of water-retaining chambers, a motor, a pump driven by

said motor, means connecting said pump with each of said chambers, a valve housing having a port communicating with each of said chambers, valve means in said housing for selectively closing one or the other of said ports, and drying means in one of said chambers, the combination of control means for connecting said drying means to said motor to be driven thereby, and means interconnected with said control means for moving said valve means to open the port communicating with said one chamber and to close the port communicating with the other chamber when said drying means is operating.

3. In apparatus comprising a plurality of water retaining chambers, mechanical operating means in each of said chambers, a single motor arranged to drive each of said mechanical means, a pump arranged to be continuously driven by the motor, and fluid conduits between the pump and each of the chambers, the combination of means for controlling the operation of each of said mechanical means, a valve arranged to connect the pump alternatively with one of the chambers and simultaneously close the connection to the other of said chambers, and an interlocking connection between the valve and control means arranged to prevent an open connection between the pump and one of said chambers when the mechanical means in the other chamber is in operation.

4. In apparatus comprising a plurality of water retaining chambers, mechanical operating means in each of said chambers, a single motor arranged to drive each of said mechanical means, a pump arranged to be continuously driven by the motor, and fluid conduits between the pump and each of the chambers, the combination of means for controlling the operation of each of said mechanical means, a valve arranged to connect the pump alternatively with one of the chambers and simultaneously close the connection to the other of said chambers, an interlocking connection between the valve and control means arranged to prevent an open connection between the pump and one of said chambers when the mechanical means in the other chamber is in operation, and a manual control for the valve permitting it to be operated before the interlock comes into play.

CHARLES E. MORGENSTERN.
